RINSING APPARATUS

Herio L. Caruolo, Johnston, R. I.

Application June 17, 1937, Serial No. 148,755

8 Claims. (Cl. 141—3)

This invention relates to improvements in rinsing devices and more particularly to those in general use in soda fountains. Ordinarily in soda fountains the rinsing or cleaning of glasses results in frequent glass breakage and as the glasses in use in soda fountains are expensive the breakage is quite an item of expense.

The primary object of this invention is to provide a construction that will materially reduce or eliminate the glass breakage.

In the drawing:

Fig. 1 is a more or less fragmentary view of a rinsing apparatus with parts broken away more readily to show the glass rinsing mechanism with the present improvements;

Fig. 2 is a plan view of the ring or spider shown in Fig. 1;

Fig. 3 is a detailed sectional view showing the rubber or other tube, hereinafter to be specifically described, as it is retained in position on the ring or spider; and

Fig. 4 is a perspective view of the rubber or other tube per se.

The numeral 1 indicates the rinsing apparatus in general, 2 the inlet pipe for the rinsing water, and 3 the outlet or waste pipe. Within the outer casing of the rinser is rigidly connected a series of hollow tubes or pipes 4 connecting at their upper end with a hollow tube or pipe 5. Extending upwardly within the casing is a centrally located tube 6 having a restricted opening at its upper end through which water is forced into the glass shown in dotted lines at 7. Also the more or less circular pipe 5 is provided with a series of openings 8 through which the water passes to rinse off the outer surface of the glass 7. Pivotedly connected to the upstanding tube or pipe 6 are bifurcated arms 9 which are spring held in such a manner that their outer ends are normally held in a relatively elevated position, the valve connecting with the inlet pipe 2 being closed at such time. When the arms 9 are forced downwardly due to the downward pressure upon the glass 7 which acts indirectly upon the arms 9 through the spider or ring 10, the valve (not shown) for the pipe 2, is opened and as a consequence thereof water or other cleansing liquid is forced through the restricted opening in the tube 6 and also through the openings 8 thus to cleanse the glass both on the inside and on the outside thereof. The ring or spider 10 is provided with spaced (and as herein shown three) webs or radially disposed arms 11 integral with a centrally located ring 12. Each web or arm 11 is provided with retaining lugs 13 as

shown in Figs. 2 and 3. The retaining lugs 13 serve to retain the rubber or other tubes 14 in position by engaging in the central opening 15 thereof. The rubber or other tubes 14 rest on bars or horizontal supports 16 which are integral with the webs or arms 11. The parts just described are in common use in soda fountains and applicant makes no claim to the construction so far described.

10 The rubber or other tubes 14 are circumferentially spaced and provided with a series of closely spaced upstanding lugs or projections 17 and 18 that may extend lengthwise of the tube, thus being spaced radially of the rinsing apparatus. 15 Six short projections 17 are shown although the number may be varied and they are not necessarily equally spaced apart although so shown in the drawing. At one end of each tube, which in use constitutes the outer end of the tube, is a projection 18 which is shown as being of a greater height than the others or shorter lugs or projections 17.

The tubes 14 with their projections 17 and 18 can be conveniently made in a properly constructed rubber mold.

In actual use a glass is pressed downwardly on the upper surfaces of the three or more tubes (two only being shown in Fig. 2), the edge of the glass seating between closely adjacent lugs or projections 17 or 18. As hereinbefore described, without limiting or confining projections 17 or 18, glasses frequently when pressed downwardly on the rubber tubes now in common use, slide along the tubes and forcibly contact the upright tubes 4 or the inner surface of the casing which chips or cracks the glass adjacent to its edge. The tendency of the glass to slide along the rubber tubes now in common use is accentuated by reason of the presence of a slippery or greasy film deposited on the rubber tubes due to ice cream or syrups in common use in soda fountains. Obviously when using the tubes of the type illustrated in detail in Figs. 3 and 4 of the drawing, the edge of the glass being seated between adjacent projections 17 and 18, the tendency of the glass to slide along the tubes is eliminated. Should a glass snap over a projection 17, it will engage the higher projection 18 which will prevent contact of the glass edge with the upright tubes 4 or the inner surface of the casing or container.

The projections 17 and 18 are so spaced that the edge of an article to be rinsed, such as a glass, will be seated between adjacent projections and the said projections are of such a

height that even the presence of grease will not cause the glass to slide along the surface of the rubber tube or seat and become broken. Furthermore, the said projections 17 are of substantial cross-section and sufficient to serve as a substantial abutment thus acting as a definite stop to any tendency of the glass to slide along the upper surface of the seat. The just mentioned characteristics are substantially different and perform a substantially different function than would result from a mere roughness of a rubber or other surface.

Although as hereinbefore described, the tube 14 is preferably of rubber, a more or less non-resilient core can be employed which would be, preferably, covered with felt or some yielding material. In such case the core would have corrugations or projections to serve the purpose of the projections 17 and/or 18 of the tube 14. The said corrugations or projections could themselves be covered with felt or extend through openings in the felt coverings.

As hereinbefore indicated, it is preferable that the outer surface of the tube to be contacted by the glass to be rinsed, be of a more or less soft or yielding material and although a molded rubber tube provides a convenient means for effecting the desired purpose, within the scope of the invention, other materials may be employed.

The projections 17 and 18 and their arrangement as shown, serve as a convenient means for retaining the glasses as described in preventing forcible contact with the casing or upright tubes through which the water or other cleansing fluid is forced into and around the glass; however, the precise arrangement and construction of the projections is not essential as a more or less uniformly corrugated surface would serve the purpose in that it would provide seating recesses for the edge of the glass and consequent shoulders for preventing the glass edge from sliding along the upper surface of the rubber tubes. Obviously the invention is not limited to the details of construction shown and described, the appended claims defining the intended scope of the invention.

I claim:

1. A rubber tube adapted to be applied to a rinsing apparatus and having a centrally disposed opening extending longitudinally thereof, and closely adjacent upstanding projections on the outer surface of the tube, said projections being so spaced and of such a height as to accommodate portions of articles to be rinsed between adjacent projections and prevent the said articles from sliding along the seat.

2. A rubber tube adapted to be applied to a rinsing apparatus and having a centrally disposed opening extending longitudinally thereof, and closely adjacent upstanding projections on the outer surface of the tube, at least one of such projections being longer than others of said projections, said projections being so spaced and of

such a height as to accommodate portions of articles to be rinsed between adjacent projections and prevent the said articles from sliding along the seat.

5 3. A tube adapted to be applied to a rinsing apparatus and having a centrally disposed opening extending longitudinally thereof, the outer surface of the said tube having yielding, closely spaced projections extending outwardly of the tube, said projections being so spaced and of such a height as to accommodate portions of articles to be rinsed between adjacent projections and prevent the said articles from sliding along the seat.

10 4. A rubber tube adapted to be applied to a rinsing apparatus and having a centrally disposed opening extending longitudinally thereof, and closely adjacent and upstanding projections on the outer surface of the tube and between the ends thereof, the said upstanding projections being so spaced and of such a height as to accommodate portions of articles to be rinsed between adjacent projections and prevent the said articles from sliding along the seat.

15 5. In a rinsing apparatus a seat for articles to be rinsed, said seat being movable and having circumferentially spaced holders, rubber-like elements in the holders, said rubber-like elements having upstanding yielding projections of substantial cross-section which extend radially, said projections being sufficiently spaced and of a sufficient height to accommodate the edge of an article to be rinsed between adjacent projections, the height of the said projections being such as

20 30 to prevent slipping of the articles to be rinsed along the seat.

6. In a rinsing apparatus a seat for articles to be rinsed, said seat being movable and having circumferentially spaced holders, tubular resilient elements in the holders, said resilient elements having upstanding yielding projections between the ends thereof which extend radially, said projections being so spaced and of such a height that portions of articles to be rinsed may be accommodated between the adjacent projections and prevented from sliding along the seat.

25 7. A rinsing apparatus for articles such as drinking glasses, and including a horizontally disposed seat for the article to be rinsed, said seat having a horizontally disposed opening and yielding, longitudinally extending projections, the adjacent projections being spaced but closely adjacent.

8. A rinsing apparatus including a horizontally arranged support and resilient seats removably mounted on said supports, said seats extending radially and having short, yielding projections upstanding therefrom, the said projections being closely arranged and corresponding projections on the several seats being so spaced as to accommodate the edge of the tubular article for rinsing.
